UNITED STATES PATENT OFFICE.

ALEXANDER E. PATTERSON, OF SCRANTON, PENNSYLVANIA.

SPRING-FITTING TOOL.

1,206,137.

Specification of Letters Patent. Patented Nov. 28, 1916.

Application filed September 7, 1915. Serial No. 49,319.

To all whom it may concern:

Be it known that I, ALEXANDER E. PATTERSON, a citizen of the United States, residing at Scranton, in the county of Lackawanna and State of Pennsylvania, have invented certain new and useful Improvements in Spring-Fitting Tools; and I do hereby declare the following to be a full, clear, and exact description of the invention, such as 10 will enable others skilled in the art to which it appertains to make and use the same.

This invention relates to metal bending, and more especially to machines having a reciprocating bender with a variable die 15 face; and the object of the same is broadly to produce a single machine in which a spring leaf may be bent or "fitted" to a die or "form" and with it inserted in the tempering bath.

20 One of the objects of this invention is the production of such a machine whereby a small spring can be bent entirely by hand.

A further object of the invention is to provide the movable die with plungers which 25 automatically adapt themselves to the curvature of the fixed die.

A further object of the invention is to produce a machine which, in its several embodiments, includes plungers for engaging 30 both sides of a spring, or one side only of a spring, or the center of a rather wide spring—with yielding force in any event.

A further object of the invention is to provide an opportunity for engaging, while 35 binding the entire leaf to the form and affording means for sprinkling water upon the heated spring leaf.

A further object of the invention is to provide improved means for holding the entire 40 spring leaf on the form so that the form, leaf and tool may all be immersed in the tempering fluid when it is found desirable to temper in that manner instead of first sprinkling with water and removing the 45 spring leaf and immersing it independently of the form.

With these and other objects in view the invention consists in certain novel features of construction, combination and arrangement of parts as will be hereinafter more 50 fully described and claimed.

In the drawings, Figure 1 is a conventional view of an unfitted spring leaf ready to be bent. Fig. 2 is a view of the spring 55 leaf placed upon the form with one embodiment of the fitting tool in position, showing

in dotted lines the position of the spring leaf after being fitted. Fig. 3 is a transverse section on the line 3—3 of Fig. 2. Fig. 4 is a sectional view on the line 4—5 of Fig. 2, 60 wherein tension has not been applied, and Fig. 5 is a similar section on the same line showing the position of parts after tension has been applied. Fig. 5 is another transverse sectional view taken on the line 5—5 65 through the endmost plunger of Fig. 2, but in this view tension has not been applied. Fig. 6 is a top plan view of another embodiment of the fitting tool, providing means for engaging one side of the leaf only. Fig. 70 7 is a view in elevation of the embodiment of the tool shown at Fig. 6. Fig. 8 is a transverse sectional view taken on line 8—8 of Figs. 6 and 7. Fig. 9 is a perspective view of one of the fitting dies. Fig. 10 is 75 a view in elevation of still another embodiment of the present invention, showing a different form of spring-pressed plungers. Fig. 11 is a top plan view of the embodiment of the invention shown at Fig. 10. 80 Fig. 12 is a fragmentary view in elevation of yet another embodiment of the invention, showing a single row of spring-pressed plungers and the guides. Fig. 13 is a transverse sectional view through the form of fitting tool shown at Fig. 12 taken on line 85 13—13 of Fig. 12. Fig. 14 is a view in side elevation of an embodiment of the invention where its spring-pressed plungers are omitted, depending upon a rigid die consisting of a bar shaped to the form of the leaf to take the place of such spring-pressed plungers. Fig. 15 is a top plan view of the fitting tool without the plungers as shown 90 at Fig. 14. Fig. 16 is a transverse sectional view taken on line 16—16 of Figs. 14 and 15. 95

Like characters of reference designate corresponding parts throughout the several views.

It is well known that in the ordinary 100 method of fitting springs by hand a spring leaf as 20 is first placed upon a form as 21 and an operator upon each side employing a pair of tongs, bends down the ends of the leaf upon the form and by swinging the 105 keeper 22 to dotted line position locks the leaf in such position. Then with other tongs the two operators, working upon opposite edges of the leaf, force it down into intimate engagement with the form to conform 110 accurately to the shape desired. The leaf is then clamped upon the form by a plurality

of devices, water is sprinkled on to retain the leaf against distortion, and the leaf then immersed in oil or other tempering bath. In the drawing no attempt has been made 5 to show the form 21 or leaf 20 in any accurate proportions or technical exactness, it being understood of course that the usual and ordinary form is employed and that any form of spring leaf may be subject to the 10 treatment of the tool hereinafter described.

My improved spring fitting tool is a unitary instrument designed to take the place of both pairs of tongs and the clamping devices above mentioned, and it is hereinafter 15 described and shown in the drawings in several embodiments adapted to springs of various types. Broadly speaking, it comprises a lower or fixed die which is the "form" to which the spring is to be bent, an upper 20 or movable die having spring-pressed plungers, and a pair of tongs 28 for forcing these dies toward each other; and in any embodiment said tongs may have a pair of crossing handles 10 and 11 pivoted to each other 25 and are extended into a lower jaw 13 and an upper jaw 14. Linked to the outer end of one handle, as that numbered 11, is a keeper 22 pierced with a plurality of eyes 19, any of which may be slipped over the tip of the 30 upper handle 10 to hold the handles and therefore the jaws against spreading apart. I have shown the several embodiments of my tool as employing but a single pair of tongs as just described, located at about its 35 mid-length, and I find the same sufficient for all ordinary purposes.

In the embodiment shown in Figs. 2 to 5 inclusive, the lower or fixed die 21 constitutes the form over which the spring leaf 20 is to be bent, and the center of this die 40 overlies the lower jaw 13 of the tongs. The upper or movable die includes a bar 23 which is of nearly the same length as the lower die 21 and which in this embodiment 45 is shown as straight, and the center of this bar passes over the upper jaw 14 and is secured thereto by a bolt 16 which passes through the bar and through this jaw.

Located about the bar 23 are a plurality 50 of plungers 24 which are yokes of substantially inverted U formation with the bar 23 resting normally in the bend of the U. The plungers are connected with the bar 23 by means of bolts 25, which rise rigidly from 55 the bar, pass loosely through holes in the bends or arches of the yokes or plungers, and are surrounded by coiled expansive springs 26 between the top of the plungers 24 and the tension nuts 27.

It will thus be seen that each of the plungers 24 is capable of independent resilient 60 movement upward relative to the bar 23 to which is attached the tongs 28, so that as the tongs are manually closed the leaf 20 will 65 be forced from the position shown at full

lines in Fig. 2 to the position shown in dotted lines in engagement with the form 21. To enable the plunger 24 to properly act upon both sides of the leaf, feet in the shape of shoulders 29 are formed which bear upon the opposite edges of the leaf, and down-turned extremities 30 which serve as guides and positioning members so that the leaf 20 will be in proper lateral relation to the form 21. 70

When in this position the keeper 22 may be swung to the position shown in dotted lines at the left of Fig. 3, and the entire tool, leaf and form may be immersed in the tempering fluid, or water may be sprinkled 80 upon the leaf 20 by reason of the open formation of the tool after which the leaf 20 may be removed from the form and independently immersed in the tempering fluid. 75

For some springs as, for instance, very wide springs a device which will engage both sides of the spring leaf simultaneously is found inconvenient in operation and for supplying the need of such a contingency an embodiment of my invention is provided 90 having a row of plungers engaging only the one side of the spring and it is possible to use two of such tools, one upon each side of the leaf as indicated at Fig. 6. The tool itself comprises a bar 31 similar in all respects to the bar 23 with plungers 32 mounted thereon by means of bolts 33 and controlled by springs 34. The plunger 32 is provided with a single foot 35 and its extremity or guide 30' positioned to engage 100 one edge of the leaf 20 as shown at Fig. 8, and if a similar tool is applied to the other side it is obvious that both sides will then be under compression simultaneously but by two operators. The tongs 28 are attached 105 to the latter tool the same as the tool shown at Figs. 2 to 5 inclusive.

At Figs. 10 and 11 the tool is shown with a plunger of different type. At those figures the bar 36 is similar to the bars 23 and 31, but it has holes for loosely receiving two rows of spring-pressed plungers in the form of bolts 37 having coiled expansive springs 38 located between the bar and the bolt-heads, and provided with tension nuts 110 39 whereby the heads of the bolts 37 are pressed upon the spring leaf 20 by the tongs 28 with the necessary pressure. Guides 40 are carried by the bar for properly positioning the tool relative to the leaf and form. 115

At Fig. 12 a further embodiment is shown having a bar 41 carrying a single row of spring-pressed plunger bolts 42 with a guide 43 adapted to engage one edge of the spring. It is obvious that the guide 43 may be 125 omitted and the single row of spring-pressed plungers 42 simply employed to engage the center line of the spring leaf holding its position. In all the forms the spring leaf will be yieldingly held to position and may 130

be retained in such position by being tempered.

In Figs. 14 to 16 inclusive a form of fitting tool is shown without resilient plungers, 5 a bar 44 being employed curved to fit the required curvature of the spring, and provided with openings 45 for sprinkling water through when desired. This form is also attached to the tongs in the same manner as 10 heretofore described and guides 46 are likewise provided and for the same purpose.

It is believed that the utility and operation of the tool has been sufficiently described in the description of the tool itself, 15 and that further description of such operation will not be necessary.

I claim:—

1. In a bending tool, the combination with upper and lower dies; of a pair of tongs 20 comprising two handles crossing and pivoted to each other and extended into jaws whereof the lowermost underlies the lower die and the uppermost is provided with a hole, a bolt passing through said hole and 25 engaging the upper die, and a keeper linked to the end of one handle and having eyes adapted to be engaged with the end of the other handle, for the purpose set forth.

2. In a bending tool, the combination with 30 a rigid lower die whose upper face constitutes a form, and a pair of tongs whose lower jaw is connected with said die at the mid-length of the latter; of an upper die connected with the upper jaw of the tongs 35 and adapted to shape the work upon said form, and guides depending from the upper die at its edge and adapted to pass and contact with the edge of the work and form as the tongs are closed.

3. In a tool for bending spring leaves, the 40 combination with a rigid lower die whose upper face is curved to constitute a form; of a bar overlying said die, a plurality of plungers movably mounted on and projecting below said bar, expansive springs bearing 45 said plungers with yielding force toward said form, a foot on each plunger to engage one side of the leaf resting on said form, and means for pressing the bar toward the form.

4. In a tool for bending spring leaves, the combination with a curved form, a bar overlying the same, and means for pressing the bar toward the form; of a series of bolts rising from said bar, a series of plungers 55 each having its upper end slidably mounted on one bolt and its lower end provided with a foot to engage one side of the leaf resting on said form, and a guide projecting below the foot to engage the edge of said leaf and 60 form, and an expansive spring coiled on the bolt between its upper end and the upper end of said plunger.

5. In a tool for bending spring leaves, the combination with a curved form, a bar overlying the same, and means for pressing the bar toward the form; of a series of bolts rising from said bar, a series of plungers of inverted U-formation standing astride said bar and each mounted loosely on one of said 70 bolts, expansive springs on the latter between its upper end and the plunger, and shoulders on the plunger-arms forming feet engaging the work near its edges and extensions passing by said edges, for the purpose 75 set forth.

In testimony whereof I affix my signature.
ALEXANDER E. PATTERSON.
